CLAIM

The ornamental design for a display screen or portion thereof with graphical user interface, as shown and described.

DESCRIPTION

FIG. 1 is a front view of a display screen or portion thereof with graphical user interface showing our new design; and, FIG. 2 is a front view of a display screen or portion thereof with graphical user interface showing an alternative embodiment of our new design.

The broken lines depicting the text, various symbols, display screen, and the remainder of the graphical user interface show features that form no part of the claimed design.

1 Claim, 2 Drawing Sheets
